UNITED STATES PATENT OFFICE.

WILLIAM A. ECKERT, OF BUFFALO, NEW YORK.

CUTLERY-HANDLE.

1,333,066.

Specification of Letters Patent.

Patented Mar. 9, 1920.

Application filed September 15, 1915. Serial No. 50,756.

To all whom it may concern:

Be it known that I, WILLIAM A. ECKERT, a citizen of the United States, residing at Buffalo, in the county of Erie and State of New York, have invented new and useful Improvements in Cutlery-Handles, of which the following is a specification.

This invention relates to a handle for cutlery such as knives, forks and spoons and 10 has the object to produce a handle for this purpose which is composed principally of sheet metal, which is strong and durable in construction and which is neat and finished in appearance.

15 In the accompanying drawings: Figure 1 is a side elevation of the knife provided with my improved handle. Fig. 2 is a top plan view of the same. Fig. 3 is a vertical transverse section, on an enlarged scale, taken on line 3—3, Fig. 1. Fig. 4 is a fragmentary horizontal longitudinal section taken on line 4—4, Fig. 5. Figs. 5 and 6 are vertical longitudinal sections taken on the correspondingly numbered lines in Fig. 25 3. Fig. 7 is a perspective view of one part of the core of the handle. Fig. 8 is a similar view of another part of the core of the handle. Figs. 9 and 10 are similar views of the two sections of the jacket of the handle. 30 Fig. 11 is a cross section similar to Fig. 3 showing a slightly modified construction. Fig. 12 is a cross section, on an enlarged scale, of another modified construction of the handle taken on line 12—12, Fig. 13. 35 Fig. 13 is a vertical longitudinal section taken on line 13—13, Fig. 12. Fig. 14 is a horizontal longitudinal section taken on line 14—14, Fig. 12.

Similar characters of reference indicate 40 corresponding parts throughout the several views.

Although this handle is applicable to various kinds of cutlery the same is represented in Figs. 1 and 2, as applied to a knife 1. My improved handle is associated with the tang 2 of a knife or other kind of cutlery and may be embodied in various ways but the form which is shown in Figs. 1—10, is constructed as follows:

50 The handle comprises the tang previously referred to, a core mounted on the tang, and an inclosing jacket or shell which surrounds

the tang and core and produces the finished exterior of the same. In addition to this means are provided for producing a tight 55 joint between the jacket and the tang for excluding water from the interior of the handle. The core in the form of handle shown in Figs. 1—10 comprises a U-shaped member or frame the arms 3—3 of which are 60 arranged lengthwise above the upper and lower longitudinal edges of the tang while the bow or cross piece 4 thereof engages with the rear edge of the same, and two side plates 4 which are mounted on opposite sides 65 of the frame. Each arm of the frame is provided along its longitudinal center with an inwardly opening longitudinal groove 5 in which is seated one of the longitudinal edges of the tang and the bow of the frame 70 is also provided along its longitudinal center with an inwardly opening longitudinal groove 6 which receives the rear edge of the tang, thereby holding these parts against lateral movement relatively to each other 75 when the same are assembled. The tang may have its upper and lower longitudinal edges arranged in any desired position relatively to each other but these edges preferably converge forwardly, and when these 80 edges are engaged by the arms of the frame the latter also converge forwardly, thereby preventing the frame and the parts mounted thereon from being withdrawn lengthwise and rearwardly off from the tang. It is desirable to positively interlock the arms of 85 the frame with the tang, so that the same cannot move lengthwise on each other this being preferably accomplished by means of inwardly projecting teats or projections 7 90 formed on the arms adjacent to the front ends thereof and engaging with notches or recesses 8 formed in the upper and lower edges of the tang, as shown in Fig. 6. When the frame arms are thus held in engagement with the tang by means of these locking teats rearward movement of the frame and the parts mounted thereon is positively prevented, thereby holding the several parts 95 of the handle in their proper position.

The opposite longitudinal edges of each frame arm are bent laterally so as to form longitudinal flanges 8, 8 which diverge outwardly from opposite sides of the compa-

ion groove of the respective arm, and the opposite longitudinal edges of the bow of the frame are likewise bent laterally so as to form longitudinal locking flanges 9 thereon which diverge outwardly from the companion groove in this bow, as shown in Figs. 3 and 4. The flanges of the frame arms preferably terminate short of the front ends of these arms, as shown in Figs. 5, 6 and 7, for purposes which will presently appear. This frame is preferably constructed from a single piece of sheet metal in any suitable and well known manner. Each of the side plates of the core is also preferably constructed from a single piece of sheet metal by stamping in any suitable manner, so that the same is curved outwardly slightly in cross section and provided at its upper and lower longitudinal edges with channels or hook-shaped flanges 10 which face each other on the inner side of this plate, and a transverse lip 11 projecting inwardly from the front end of this plate. The channels or hook flanges of each side plate engage with the corresponding flanges 9 of the frame arms on one side of the tang for the purpose of connecting the side plate with the frame and retaining the arms of the latter in position on the tang. These hook flanges of the side plates converge forwardly to conform to the flanges of the frame arms. These hook flanges of the side plates are applied to the companion flanges of the frame arms by slipping these hook flanges over the frame flanges from the front end of the latter until these parts are tightly drawn together with a wedging action and the frame arms are clamped against the upper and lower edges of the tank, thereby securely connecting the core with the tang and preventing these parts from becoming separated. When a comparatively inexpensive handle is desired the parts just described will answer the purpose of a handle for cutlery of low grade, but for higher grades of cutlery a jacket or shell is provided which incloses the core and tang and produces not only a neat and finished appearance but also a better grip for the hand. This jacket may be variously constructed but in its preferred form the same comprises two hollow sections each of which is constructed of sheet metal so as to form an outwardly curved side wall 12, upper and lower longitudinal flanges 13, 13 projecting inwardly from the upper and lower edges of the side wall, a rear end flange 14 projecting inwardly from the rear end of the side wall and a front lip 15 projecting inwardly from the front end of the side wall. The two sections of the jacket are applied to opposite sides of the core and tang so that the side walls of these sections engage with the side plates of the core and the flanges of the jacket sections overlap each other on

the outer side of the frame arms, while the end flanges of the jacket sections overlap one another on the outer side of the frame bow and the front lips of these jacket sections engage with opposite flat sides of the tang at the front end thereof. Each of the jacket sections is preferably provided with beads 16 arranged between the marginal part of its side wall and the longitudinal and end flanges thereof. The two jacket sections are retained in this position by crimping the outer set of flanges of one jacket section inwardly against shoulders formed by the beads 16 on the other jacket section at the junction between the side wall and flanges of the last mentioned jacket section, as shown in Figs. 3 and 4.

When the two body sections are thus interlocked with each other the same completely inclose the core and tang of the body and produce a neat and finished appearance as well as a smooth and even surface which is adapted to be grasped by the hand.

When the parts are thus assembled the lips at the front end of the core side plates engage with the opposite sides of the tang at a distance rearwardly from the point where the tang is engaged on its opposite sides by the lips at the front ends of the jacket sections. In order to prevent any water from leaking through the joint between the tang and these lips into the interior of the handle a filling or packing is arranged in the spaces between the jacket lips and the core lips on opposite sides of the tang and in front of the flanges of the frame arms. The lips at the front ends of the side plates and the shoulders formed by the front ends of the frame flanges form stops which hold the cork filling or packing sections against rearward movement on the tang. This filling preferably consists of sections 17 of cork or other non-absorbent material which filling is placed in the proper position on opposite sides of the tang preparatory to applying the two sections of the jacket so that when these last mentioned sections are secured to the core and tang the cork filling will be compressed between the tang and the lips of the jacket sections so as to effectually prevent the entrance of water at this point into the interior of the handle.

Instead of constructing the longitudinal flanges of the core side plates in the form of hooks as shown in Figs. 3 and 8, these flanges may be made parallel with the upper and lower edges of the tang or at right angles to the flat faces thereof, as shown at 18 in Fig. 11. In this last mentioned construction the longitudinal flanges of the core side plates do not become interlocked with the flanges of the frame arms and it is therefore necessary in this form of the core side plates to employ the inclosing jacket

around the core and tang for the purpose of holding the several members of the core in engagement with the tang.

In the modified construction of my invention shown in Figs. 12, 13 and 14 the side plates of the core are omitted and the two sections of the jacket or shell engage with the flanges of the frame arms and bow and with the front part of the tang. The jacket sections in this construction are provided with internal shoulders 19 between their side walls and their flanges which shoulders are held in engagement with the frame flanges by lapping the flanges of one jacket section over the flanges of the other jacket section and clenching the edges of the outer pair of jacket flanges against flanges of the other jacket section.

Entrance of water into the interior of the handle may be prevented by entirely filling the spaces between opposite sides of the tang and the inner surfaces of the jacket side walls and frame by means of two filling sections 20 composed of cork or other non-absorbent material so that these filling sections extend from the front end of the handle to the rear end thereof, as shown in Figs. 12, 13 and 14. If desired, however, these filling sections may be confined to the front part of these spaces so as to prevent the entrance of water into the handle between opposite sides of the tang and the lips at the front ends of the jacket sections. When the interior of the handle is only partly filled with a non-absorbent filling as just described that part of the filling at the right of the dotted line 21 in Fig. 14 may be omitted while that part of this filling at the left of this line may be retained.

My invention renders it possible to manufacture strong and serviceable handles which are low in cost, neat in appearance and not liable to become detached from the cutlery of which they form a part under the most severe usage to which they may be subjected. Inasmuch as the main parts of this handle are all constructed of sheet metal the same can be produced expeditiously by the usual stamping operations resulting in a handle which is much lighter than one which is made of solid material as well as less expensive without sacrificing any of the qualities required in a high grade handle.

I claim as my invention:

1. A cutlery handle comprising a tang, a core engaging with said tang, a jacket engaging with said tang and core, and means to maintain and confine a non-absorbent filling between the front parts of the core, tang and jacket.

2. A cutlery handle comprising a tang, a core having a U-shaped frame the arms of which engage the longitudinal edges of the tang, and a jacket composed of two hollow sections which are applied to said frame from

opposite sides thereof and are provided with flanges which lap one over another.

3. A cutlery handle comprising a tang, a core having a U-shaped frame which is grooved lengthwise on its inner side and has the grooves of its arms engaging with the opposite longitudinal edges of the tang and the groove of its bow engaging with the outer end of said tang, and a jacket inclosing said frame and tang and comprising two sections arranged on opposite sides of said frame and tang and having flanges on their opposing inner sides which are interlocked with each other, and lips at their front ends which engage with opposite sides of the tang. 70 75 80

4. A cutlery handle comprising a tang, a core having a U-shaped frame which is grooved lengthwise on its inner side and has the grooves of its arms engaging with the opposite longitudinal edges of the tang and the groove of its bow engaging with the outer end of said tang, and a jacket inclosing said frame and tang and comprising two sections arranged on opposite sides of said frame and tang and having flanges on their opposing inner sides which are interlocked with each other, lips at their front ends which engage with opposite sides of the tang, and fillings arranged in the spaces between said lips, tang and the front ends of said jacket sections. 90 95

5. A cutlery handle comprising a tang, a core applied to said tang and having a U-shaped frame the arms of which engage with opposite longitudinal edges of said tang and side plates applied to the corresponding edges of said arms, and a jacket inclosing 100 said core and tang.

6. A cutlery handle comprising a tang, a core applied to said tang and having a U-shaped frame the arms of which engage with opposite longitudinal edges of said tang and side plates applied to the corresponding edges of said arms, a jacket inclosing said core and tang, and fillings of non-absorbent material arranged between the front part of 110 said core, tang and jacket. 105

7. A cutlery handle comprising a tang, a core applied to said tang and having a U-shaped frame the arms of which engage with opposite longitudinal edges of said tang and are provided with laterally projecting flanges and side plates having longitudinal hook flanges which engage with the corresponding flanges of said arms, and a jacket inclosing said tang and core and composed 115 120 of sections which interlock with each other.

8. A cutlery article having a handle comprising a metallic skeleton core frame, a pair of hollow metal handle sections applied to opposite sides of said core and provided 125 with flanges constructed and arranged in locked engagement on said core, and a blade having a tang affixed to said core frame.

9. A cutlery article having a handle comprising a rigid skeleton core-frame and a 130

4
pair of metal shell-sections applied to and in-
casing said frame, said sections being pressed
into interlocking engagement on said core-
frame and the latter forming a rigid backing
5 along the juncture of the sections, and a
blade having a tang engaged with said core-
frame.

10. A cutlery article having a handle com-

prising a metallic core frame of skeleton
formation and of channel section, a pair of 10
hollow metal handle sections applied to op-
posite sides of said core and provided with
flanges adapted for interlocking engagement
to unite the sections on said core, and a blade
having a tang affixed to said core frame. 15

WILLIAM A. ECKERT.
